UNITED STATES PATENT OFFICE.

WILLIAM A. MALONEY, OF NEEDHAM, MASSACHUSETTS.

DETACHABLE HEEL.

1,369,529.

Specification of Letters Patent. Patented Feb. 22, 1921.

Application filed May 24, 1920. Serial No. 383,668.

To all whom it may concern:

Be it known that I, WILLIAM A. MALONEY, a citizen of the United States, residing at Needham, in the county of Norfolk and 5 State of Massachusetts, have invented a new and useful Detachable Heel, of which the following is a specification.

This invention relates to a detachable heel and more particularly to improved devices 10 for detachably securing such a heel to a shoe.

It is the object of my invention to provide improved fastening devices for securing a heel to a shoe in such a manner that it will be firmly held in place while, at the same 15 time, it may be conveniently removed and replaced when desired. A further object of my invention is to provide a construction in detachable heels which may be easily and economically manufactured and which is 20 adapted to commercial production in large quantities.

My invention further consists in certain arrangements and combinations of parts hereinafter described and more particularly 25 pointed out in the appended claims. A preferred form of my invention is shown in the drawings in which,

Figure 1 is a partial longitudinal sectional elevation of a shoe with my improvements 30 embodied therein;

Fig. 2 is a bottom view of the permanent part of the heel;

Fig. 3 is a plan view of the detachable heel;

35 Figs. 4 and 5 are transverse sectional elevations of the permanent and detachable parts of the heel respectively, and

Figs. 6, 7 and 8 are perspective views of detail parts to be described.

40 Referring to the drawings, I have shown parts of a shoe 10 having a heel portion or lift 11 permanently secured thereto and I have also shown a detachable heel portion or heel proper, marked 12.

45 The heel 12 is provided with a plurality of lugs or projections 13 fitting corresponding openings 14 in the permanent heel lift 11. A fastening member 15 is also firmly secured in the heel 12, with its enlarged head 16 projecting above the upper surface of the heel.

50 When the heel is formed of rubber, the projections 13 and fastening member 15 are preferably molded into the rubber in the process of manufacturing the heel. For 55 this purpose, the member 15 is provided with laterally projecting portions 17, in which

openings may be formed to permit the rubber to be more firmly bedded around the fastening member. The member 15 is conveniently formed from a single piece of sheet 60 metal by simple punch or press operations.

When the device is to be used for a leather heel, the member 15 is to project through an opening in the upper lift of the heel 12 and is to be firmly secured in place thereby. 65

A locking plate 20 is mounted to slide in a shallow recess or depression 21 in the under side of the heel lift 11 and is secured in position by a U-shaped strap or holder 22 projecting downward through an opening in the 70 lower lift 11.

The holder 22 has a slot 23 adapted to receive the head 16 of the fastening member 15 and the lock plate 20 has a slot 24 enlarged at one end as shown at 25 and adapted to receive the head 16 when the portion 25 is aligned with the slot 23 of the holder 22. 75

The plate 20 is also provided with lugs or projections 26 which limit outward movement of the plate by engagement with the 80 holder 22, and with a down turned end 27 by which the plate may be drawn outward for detaching the heel. The slot 24 in the plate 20 may have an irregular or wavy outline as shown in Figs. 2 and 7, which makes 85 it less liable to accidental displacement.

Having described the construction of my improved heel and the fastening devices therefor, the use and operation thereof will 90 be readily apparent.

When the heel 12 is to be attached to the shoe, the plate is drawn forward until the lugs 26 engage the holder 22, at which point the enlarged portion 25 of the slot 24 is disposed beneath the slot 23 in the holder 22. 95 The heel is then placed in position with the lugs 13 inserted in the openings 14 and the head 16 of the fastening member projecting through the slot 23 and into the enlarged portion 25 of the slot 24. The plate 20 is 100 then pushed rearward which clasps the head 16 within the slot 24 and prevents withdrawal thereof. The heel is thus secured in place by the lock plate 20 and is prevented from angular displacement by the lugs 13. 105

The heel 12 is preferably formed with a slightly concave upper surface so that the parts will be held under a certain degree of tension when locked together.

Having thus described my invention, it 110 will be evident that changes and modifications thereof may be made by those skilled

in the art within the spirit and scope of my invention as set forth in the claims, and I do not wish to be otherwise limited to the details herein disclosed but what I claim

5 is—

1. In a shoe, a heel comprising a permanent portion and a detachable portion, a metal fastening member fixed in one portion and having an enlarged head, a locking plate
- 10 mounted to slide in the other portion and having a slot therein enlarged at one end to admit the head of said fastening member when the plate is drawn forward out of normal position, and projections on one portion
- 15 coöperating with recesses on the other portion to prevent angular displacement of the parts, said plate when in normal position engaging said head and locking the parts together.
- 20 2. In a shoe, a heel comprising a permanent portion and a detachable portion, a metal fastening member fixed in one portion and having an enlarged head, a locking plate

having a slot therein enlarged at one end, and a holder for said plate secured to the 25 other heel portion and also having a slot therein, said fastening member extending through the slot in said holder and being clasped in the slot in said plate when the parts are assembled and in normal locked 30 position.

3. In a shoe, a heel comprising a permanent portion and a detachable portion, a metal fastening member fixed in one portion and having an enlarged head, a locking plate 35 having a slot of irregular outline therein enlarged at one end to receive the head of the fastening member when the plate is drawn forward out of normal position, and a holder for said plate, secured to the other 40 heel portion, said fastening member being clasped in said irregular slot when the parts are assembled and in locked position.

In testimony whereof I have hereunto affixed my signature.

WILLIAM A. MALONEY.
